Ferdinand Von Leicht

UNITED STATES PATENT OFFICE.

FERDINAND VON LEICHT, OF SAN FRANCISCO, CALIFORNIA.

MEANS OF PROPELLING SHIPS.

SPECIFICATION forming part of Letters Patent No. 230,160, dated July 20, 1880.
Application filed May 6, 1880. (No model.)

To all whom it may concern:

Be it known that I, FERDINAND VON LEICHT, of San Francisco, in the county of San Francisco and State of California, have invented a new and useful Means of Propelling Ships, of which the following is a specification.

My invention consists of a rectangular box or paddle-house attached to each side of the ship below the water-line thereof, in which is placed a flat blade or paddle worked by horizontal transverse pistons connected to each end of the paddles in an alternate reciprocal manner by direct connections with the engines.

The ends of the pistons are connected to the paddles by wrist-pin joints, so that each end of the paddle or blade is worked backward and forward in an alternate manner and independent of the opposite end, which forces or draws the water against the sides of the ship or paddle-boxes, and thus the ship is propelled, all of which, together with other details of construction and operation, will hereinafter more fully appear.

Referring to the accompanying drawings, Figure 1 is a sectional plan view. Fig. 2 is a sectional side view.

The rectangular boxes or tubes A, I construct of iron, securely attached to the sides of the ship below the water-line. They are provided with water-tight doors B B, which, when open, set in a ledge made in the extended portion of the iron frame of which the boxes are composed. Each of these doors is provided with a curved arm, a, which extends inwardly, passing through stuffing-boxes, and when the doors are wide open and set close within the rabbet of the frame no sea can force them back or outwardly, the object of these doors being to close the tubes or boxes and make them water tight, in case of disarrangement of the blades, when the water is drawn out through an inside man-hole, b, into the hold of the vessel or conducted away by means of a hose, pipe, or other conductor.

The blades D, I construct of flat plates of

iron, the length and width of which are made to conform to the width and length of the paddle-box, and admit of closing the doors.

The operating-pistons B' B' are connected, two in number, at each end of the blades, near the upper and lower corners thereof, by means of wrist-pin joints C C. The pistons pass through stuffing-boxes in the plate of the boxes and the sides of the ship, and are connected at their inner ends to the piston-rods of the engines of the ship, by which action is given to the blades, causing them to work alternately backward and forward, following each other in succession, so that while one end of the blades are retained in a given position against the sides of the paddle-boxes their opposite ends move in a contrary direction across the tube, forcing out or expelling the water with great velocity from one end of the tube or the other, and thereby motion is imparted to the vessel.

The blades or paddles may be set in a horizontal, vertical, or inclined position, and the piston of the blades made to conform to the construction of the ship or vessel, and be employed with or without the paddle-boxes, the link-connections of the ends of the pistons with the ends of the blades being such as to admit of the free movement at the end of the stroke, as described.

Having thus described my invention, what I claim, and desire to secure by Letters Patent, is—

The rectangular paddle-box A, provided with doors B B and man-hole b, in combination with the blade D and pistons B' B', all constructed and arranged to operate as and for the purposes specified.

In testimony that I claim the foregoing I have hereunto set my hand and seal, this 24th day of April, 1880.

FERDINAND VON LEICHT. [L. s.]
